United States Patent Office

Des. 182,673
Patented Apr. 29, 1958

182,673

PAN OR SIMILAR ARTICLE

Richard S. Latham, Chicago, Ill., assignor to Ekco-Alcoa
Containers Inc., Wheeling, Ill., a corporation of Illinois

Application July 29, 1957, Serial No. 47,133

Term of patent 14 years

(Cl. D44—1)

Fig. 1 is a top plan view of a pan or similar article showing my new design.

Fig. 2 is a sectional view taken on line 2—2 of Fig. 1. The essential features of the design reside in the portions shown in full lines.

I claim:

The ornamental design for a pan or similar article, as shown and described.
